ATTORNEY

UNITED STATES PATENT OFFICE

133,609

DESIGN FOR A VENETIAN BLIND

Thelma J. Black, Dallas, Tex.

Application March 2, 1942, Serial No. 106,052

Term of patent 14 years

To all whom it may concern:

Be it known that I, Thelma J. Black, a citizen of the United States, residing at Dallas, in the county of Dallas, State of Texas, have invented a new, original, and ornamental Design for a Venetian Blind, of which the following is a specification, reference being had to the accompanying drawing, forming part thereof.

I claim:

The ornamental design for a Venetian blind, as shown.

THELMA J. BLACK.
